REFRIGERATING APPARATUS

John A. Grier, New York, N. Y., assignor to Frigidaire Corporation, Dayton, Ohio, a corporation of Ohio

Application December 30, 1930, Serial No. 505,494

4 Claims. (Cl. 62—115)

This invention relates to refrigerating apparatus and more particularly to improved structural features in the refrigerant liquefying portion of the apparatus.

One of the objects of the invention is to provide an improved refrigerating system having improved means for compressing and cooling the refrigerant.

Another object of the invention is to provide an improved refrigerant compressor.

Another object of the invention is to provide an improved condenser and cooling system of a novel type.

A still further object of the invention is to provide a combined condenser and inter-cooler for a domestic refrigerator.

Further objects and advantages of the present invention will be apparent from the following description, reference being had to the accompanying drawings, wherein a preferred form of the present invention is clearly shown.

In the drawings:

Fig. 1 is a sectional view of a portion of a refrigerator incorporating one embodiment of the invention;

Fig. 2 is a sectional view of the sealed unit shown in Fig. 1;

Fig. 3 is a sectional view on the line 3—3 of the compressor shown in Fig. 2;

Fig. 4 is a sectional view on the line 4—4 of Fig. 2;

Fig. 5 is a top view of the apparatus shown in Fig. 1 with the cover removed;

Fig. 6 is a sectional view through a portion of the sealed unit showing a modified form of compressor and connecting passages;

Fig. 7 is a sectional view on the line 7—7 of Fig. 6;

Fig. 8 is a top view of a modified form of the invention with the motor, cooling fan, and cowlings removed;

Fig. 9 is a section along the lines 9—9 of Fig. 7; and

Fig. 10 is a section along the lines 10—10 of Fig. 7.

Referring to the drawings and more particularly to Fig. 1, there is shown a refrigerator cabinet 20 having a slideable removable top portion 21 upon which a sealed motor compressor unit 22 is supported by rubber mountings 23. The compressed refrigerant is discharged from the sealed unit directly into the condenser 24 which is connected to the lower housing 25 of the sealed unit 22 by a flanged coupling 26. The condenser, better shown in Fig. 5, consists of a plurality of ser-

pentine loops 27 which are provided with a plurality of cross fins 28. The condenser is set in an inclined position, the lowest end being connected by the coupling 33 directly to the expansion valve 30 which is supported upon the removable top portion 21 of the cabinet 20 by a bracket 31. The condenser is supported in an inclined position by the supporting member 32 and the couplings 26 and 33.

A bracket 34 surrounds the upper housing 35 of the sealed unit and is clamped thereto by nut and bolt 36. The bracket 34 supports the fan motor 37 and the cooling fan 38 directly above the condenser 24. The cowling 40 surrounds the fan 38 and directs the stream of air from the fan 38 downwardly upon the condenser 24 to cool and liquefy the refrigerant which then flows by gravity to the expansion valve 30 because of the inclined position of the condenser. The refrigerant passing through the expansion valve 30 is conducted downwardly through the removable portion 21 of the cabinet 20 into the cooling unit 41 by a conduit 42.

The cooling unit 41 is provided with brine or some other suitable thermal conducting medium and has a plurality of refrigerant coils 43 therein which are connected to the conduit 42 for cooling the brine. These coils surround the recess 44 in the cooling unit 41 which is provided for freezing water or other liquid within the ice trays 45 supported on shelves 46 within the recess 44. The refrigerant in passing through the coils 43 to the brine absorbs heat therefrom and is conducted upwardly by the conduit 47 to a passage in the sealed unit 22.

The sealed unit 22 is provided with a lower housing 25 and an upper housing or cover 35. The lower housing has in general the shape of a cup and is provided near its lower edges with a plurality of ears 48 which support the sealed unit upon the rubber mountings 23. The lower housing 25 (see Figs. 2, 3 and 4) has at its upper end an outer flange 51 for supporting the upper housing 35 and an inner flange 52 which supports the plate member 53 which in turn supports the compressor 60 beneath it and an electric motor 70 upon supports 71 extending upwardly from the plate member 53. Supported by the motor supports 71 is the stator portion 120 of the motor 70 while the armature or rotating portion 121 of the motor 70 is fixed upon the shaft 72 for driving the compressor 60.

The upper portion 35 of the housing acts as a cover for the motor and has a flange 123 surrounding its skirt which is fastened to the flange 51 of the lower housing 25 by the cap screws 124. A suitable seal 105

is provided between the flange 51 and the flange 123. The upper housing 35 is provided with a plurality of ears 48 which support the sealed unit upon the rubber mountings 23. The lower housing 25 (see Figs. 2, 3 and 4) has at its upper end an outer flange 51 for supporting the upper housing 35 and an inner flange 52 which supports the plate member 53 which in turn supports the compressor 60 beneath it and an electric motor 70 upon supports 71 extending upwardly from the plate member 53. Supported by the motor supports 71 is the stator portion 120 of the motor 70 while the armature or rotating portion 121 of the motor 70 is fixed upon the shaft 72 for driving the compressor 60.

The upper portion 35 of the housing acts as a cover for the motor and has a flange 123 surrounding its skirt which is fastened to the flange 51 of the lower housing 25 by the cap screws 124. A suitable seal 105

is provided between the flange 51 and the flange 123. The upper housing 35 is provided with a plurality of ears 48 which support the sealed unit upon the rubber mountings 23. The lower housing 25 (see Figs. 2, 3 and 4) has at its upper end an outer flange 51 for supporting the upper housing 35 and an inner flange 52 which supports the plate member 53 which in turn supports the compressor 60 beneath it and an electric motor 70 upon supports 71 extending upwardly from the plate member 53. Supported by the motor supports 71 is the stator portion 120 of the motor 70 while the armature or rotating portion 121 of the motor 70 is fixed upon the shaft 72 for driving the compressor 60.

ing means 125 is provided in the flange 123 and 51 for preventing the escape of refrigerant and lubricant from the sealed unit. At the side of the housing 25 is a vertical cored passage 54 which is connected to the conduit 47 at the discharge end of the cooling coil 43. This passage 54 contains a filter screen 55 for removing the solid particles which may be in the refrigerant coming from the cooling unit 41. The cored passage 54 connects at its upper end with the cored passages 56 and 57 in the plate member 53 which conduct the gaseous refrigerant from the passage 54 to the cylinders 61 and 62 of the compressor 60.

15 The compressor 60 is of the opposed, two-cylinder, single stage, sleeve valve type and is driven by the vertical driving shaft 72. The driving shaft 72 is provided with an eccentric 64 (see Fig. 3) which is surrounded by a bearing member 65 which is provided with integral shoes 66 and 67 which slide on opposite walls of the rectangular yoke member 68. Integral with the yoke member 68, and extending from either side therefrom are a pair of pistons 90 and 91 which reciprocate within sleeves 92 and 93 which in turn reciprocate within cylinders 61 and 62 of the compressor 60. The sleeves 92 and 93 (see Fig. 2) are provided with suitable intake ports 94 and 95 which register at proper times with intake ports 96 and 97 in the upper part of the walls of the cylinders 61 and 62. These ports 96 and 97 connect with the passages 56 and 57 in the plate member 53. Substantially diametrically opposite to the intake ports are the exhaust ports 98 and 99 which are provided in the sleeves 92 and 93 and which provide access to the exhaust ports 101 and 102 in the lower portion of the walls of the cylinders 61 and 62. The sleeves 92 and 93 are reciprocated by a separate eccentric 103 which is of such a size and suitably positioned with respect to the eccentric 64 so that the intake and exhaust ports of the sleeves and the cylinder walls register a proper time with reference to the location and movement of the pistons. This eccentric 103 is keyed to the shaft 72 and preferably leads the piston eccentric 64 by an angle of approximately 234°. The cylinders 61 and 62 are provided with cylinder heads 104 and 105 which contain relief valves 106 and 107 which are normally held in a closed position by coil springs 108 and 109 which are held pressed against a valve head by the valve covers 110 and 111, which along with the cylinder heads 104 and 105, are fastened to the cylinders 61 and 62 by cap screws 112.

16 The shaft 72 which drives the compressor 60 rotates within a large bearing 73 which is provided in a large boss 74 projecting from the plate member 53. The boss 74 supports a ball thrust bearing 75 at its upper end which carries the weight of the shaft 72 and members attached thereto. The upper end of the shaft 72 is supported within a bearing 76 which is provided in the bearing member 77 fastened by cap screws 78 to the top of the motor supports 71. The shaft 72 is drilled to provide an oil passage 79 which is provided with oil by the oil scoop 122 which rotates within the oil which collects in the lower portion of the housing 25. The shaft 72 is provided with suitable drilled passages connecting with the longitudinal oil passage 79 for supplying the bearings and the eccentric with lubricating oil. A thermostat 126 is provided which projects through the removable portion 21 of the cabinet 20 and has its lower end projecting into the brine

within the cooling unit 41. Thermostat 126 controls the starting and the stopping of the motor 70 and preferably also the motor 37 in accordance with the temperature of the brine within the cooling unit 41. When the thermostat 126 causes the motor to operate, the compressor 60 draws gaseous refrigerant up the conduit 47 through the passage 54 in the housing 25, through the passages 56 and 57 in the plate 53, through the ports 96, 97, 94 and 95 into the cylinders of the compressor which discharge the compressed gas through the ports 98, 99, 101 and 102 into the chamber within the housing 25. The compressed gas then flows from the housing 25 into the condenser 24 where it is liquefied and flows through the expansion valve 30, expands and absorbs heat within the coils 43 of the cooling unit 41 to cool the food storage compartment 19 of the cabinet 20 and to freeze liquids within the ice trays 45. When the brine within the cooling unit 41 has become sufficiently cool the thermostat 126 causes the motors 70 and 37 to stop. The apparatus positioned on top of the cabinet 20 is provided with a cover 18 having louvers at either side for admitting and discharging air.

17 In Figs. 6 to 10 inclusive is shown the apparatus as modified for an opposed two cylinder, two stage, sleeve valve compressor with an inter-cooler. In Fig. 6 there is shown a housing 131, similar to the housing 25, having a vertical cored passage 132 in the wall thereof for conducting refrigerant from the cooling unit to the plate member 133 which is somewhat similar to the plate member 53 and which has motor supports 134 extending upwardly therefrom and a boss 135 which provides the main bearing 136 for the vertical shaft 137, similar to the shaft 72, which drives the compressor. The upper housing or cover 138 is similar to the upper housing 35 of the first mentioned embodiment.

18 As shown in Fig. 7 the compressor 140 is provided with flanges 141 and 142 and fastened to the plate member 133 by the cap screws 143. The compressor 140 is provided with a large low pressure cylinder 144 and a smaller high pressure cylinder 145. The compressor is driven by the vertical shaft 137 which has an eccentric 146 keyed thereon which is surrounded by a bearing member 147 which slides transversely in a yoke 148 to reciprocate the low pressure piston 149 which is connected on one side of the yoke and the high pressure piston 150 which is connected to the opposite side of the yoke. The pistons 149 and 150, reciprocate within sleeves 151 and 152 which are reciprocated by the sleeve eccentric 153 which operates within bearing member 154 which is provided with shoes on opposite sides and bears against opposite sides of the rectangular yoke 155 which is connected to the sleeves 151 and 152 by the cap screws 156 and 157. The low pressure cylinder 144 is provided with a port 160 on its upper side which connects with the passage 161 (see Fig. 8) in the plate member 133 which in turn connects to the vertical passage 132 in the housing 131. The sleeve 151 is provided with an intake port 164 (see Fig. 10) which at suitable times registers with intake port 160 to draw refrigerant into the low pressure cylinders 144. An exhaust port 162 is provided in the sleeve 151 for discharging at suitable times refrigerant from the low pressure cylinder into the exhaust port 163 which connects with the refrigerant passage 165 in the plate member 133 which passage leads to the passage 166 connecting with the inter-cooler.

Similarly to the condenser in the first described embodiment the combined inter-cooler and condenser 170 is positioned at the side of the sealed unit and consists of a plurality of serpentine loops 171 for the inter-cooler and a plurality of serpentine loops 172 for the condenser. These are held together in a single plane by a plurality of cross fins 173 forming a flat unit which is inclined toward the expansion valve 174.

A boss 180 is provided on the lower housing 131 of the sealed unit to which the flanged coupling 175 at the inlet end of the inter-cooler is connected. The discharge end of the inter-cooler is connected by a long conduit 176 and a similar flanged coupling 177 to a second boss 178 containing a passage 179 which connects with the passage 181 in the plate member 133 which passage leads to the high pressure cylinder 145 of the compressor 140. The passage 181 connects with the inlet port 182 (see Fig. 9) of the high pressure cylinder 145. An inlet port 183 is provided in the sleeve 152 of the high pressure cylinder which registers at suitable times with the port 182 to admit refrigerant from the inter-cooler into the high pressure cylinder. An exhaust port 184 (see Fig. 9) is provided in the sleeve 152 for registering with an exhaust port 185 in the walls of the high pressure cylinder 145 from which compressed refrigerant is discharged into the interior of the lower housing 131. Relief valves 190 and 191 are provided in the low pressure head 192 and the high pressure head 193 for relieving excessive pressure which may occur at times within the low and high pressure cylinder because of unusual conditions. The compressed refrigerant within the lower housing 132 is discharged through the passage 195 in the boss 196 to which the flanged coupling 197 at the inlet end of the condenser is connected. The discharge end of the condenser is connected by the coupling 198 to the expansion valve 174 where the liquefied refrigerant expands and is conducted to the cooling unit as in the first described embodiment.

By compressing the refrigerant first in the low pressure cylinder and then cooling such com-

pressed refrigerant in the inter-cooler before it enters into the high pressure cylinder, the efficiency of the compressor and the refrigerating system in general is increased. The use of the single sleeve valve provides an improved compressor having a high efficiency and long life.

While the form of embodiment of the present invention as herein disclosed, constitutes a preferred form, it is to be understood that other forms might be adopted, all coming within the scope of the claims which follow.

What is claimed is as follows:

1. In refrigerating apparatus, the combination of a motor driven two-stage compressor, a flat inclined condenser connected to the discharge part of the high pressure stage of the compressor, an inter-cooler integral with the condenser for the compressor, and a cooling fan mounted above the combined condenser and inter-cooler for providing air circulation.

2. In refrigerating apparatus, the combination of a motor driven two-stage compressor mounted in a sealed housing, a combined condenser and inter-cooler mounted at the side of the compressor housing, and an individual motor driven cooling fan mounted above the combined condenser and inter-cooler for providing air circulation.

3. Refrigerating apparatus comprising a motor-driven, two-stage compressor mounted in a sealed housing, a combined condenser and inter-cooler mounted adjacent the sealed housing and operatively connected thereto, and fan means for circulating air over the surfaces of the combined condenser and intercooler for removing heat therefrom.

4. Refrigerating apparatus comprising a motor driven compressing means having a plurality of stages, a combined intercooler and condenser operatively connected to the compressor, an evaporating means operatively connected to the condenser and compressor, and fan means for circulating air over the surfaces of the combined intercooler and condenser for removing heat therefrom.
